(57) **CLAIM**

The ornamental design for a protective case for electronic tracking device, as shown and described.

DESCRIPTION

FIG. 1 is a perspective view including the front, top, and side of a protective case for electronic tracking device showing our new design;

FIG. 2 is a perspective view including the rear, bottom, and the opposite side of the protective case for electronic tracking device of FIG. 1;

FIG. 3 is a front elevation view of the protective case for electronic tracking device of FIG. 1;

FIG. 4 is a rear elevation view of the protective case for electronic tracking device of FIG. 1;

FIG. 5 is a side elevation of the protective case for electronic tracking device of FIG. 1;

FIG. 6 is an opposite side elevation view of the protective case for electronic tracking device of FIG. 1;

FIG. 7 is a top plan view of the protective case for electronic tracking device of FIG. 1;

FIG. 8 is a bottom plan view of the protective case for electronic tracking device of FIG. 1;

FIG. 9 is a perspective view including the front, top, and side of a protective case for electronic tracking device wherein the elements of the protective case are separated from each other;

FIG. 10 is a perspective view including the rear, bottom, and an opposite side of the protective case for electronic tracking device wherein the elements of the protective case are separated from each;

FIG. 11 is a front elevation view of the protective case for electronic tracking device wherein the elements of the protective case are separated from each;

FIG. 12 is a rear elevation view of the protective case for electronic tracking device wherein the elements of the protective case are separated from each;

FIG. 13 is a side elevation of the protective case for electronic tracking device wherein the elements of the protective case are separated from each;

FIG. 14 is an opposite side elevation view of the protective case for electronic tracking device wherein the elements of the protective case are separated from each;

(Continued)

FIG. 15 is a top plan view of the protective case for electronic tracking device wherein the elements of the protective case are separated from each; and,

FIG. 16 is a bottom plan view of the protective case for electronic tracking device wherein the elements of the protective case are separated from each.

The dashed broken lines throughout the drawing figures depict portions of the protective case for electronic tracking device that form no part of the claimed design.
